Specification for Design.

Patented June 18, 1912.

Application filed May 15, 1911. Serial No. 627,378. Term of patent 14 years.

To all whom it may concern:

Be it known that I, THOMAS M. SAVILL, a citizen of the United States, and a resident of the city of Philadelphia, in the county of Philadelphia and State of Pennsylvania, have invented a new, original, and ornamental Design for Bibs, of which the following is a specification, reference being had to the accompanying drawing.

The figure shown in the drawing represents a side elevational view of a bib showing my new design.

I claim:

The ornamental design for a bib, substantially as shown.

THOMAS M. SAVILL.
